Aspatzgood

Attorney

UNITED STATES PATENT OFFICE

WILLIAM BLADES FOREMAN, OF ELIZABETH CITY, NORTH CAROLINA

KNOCKDOWN HOGSHEAD

Application filed September 3, 1931. Serial No. 561,795.

In shipping tobacco it is usually packed in "hogsheads" commonly constructed of staves, heads and hoops in a well known manner. In the tobacco markets it becomes necessary to inspect the contents of these packages and to do so usually one or two of the staves must be removed in order to permit the contents to be inspected throughout the height or length of the package. The replacement of such staves or repair of the hogshead or package after inspection is a matter of considerable trouble, labor and consequent expense. Moreover, such containers so constructed are usually not fit for subsequent or re-use.

The object of my said invention is to provide a hogshead or container for the shipment of tobacco which shall be of a construction that can be quickly and easily opened for the inspection of its contents, can be quickly "knocked-down" for storage or packing for return for re-use, and which at the same time will be of much less weight than the usual hogshead and thus easier of handling and its use resulting in a saving of freight. A further object is to provide such a hogshead that can be quickly and easily repaired when it may become punctured or have a break in the side thereof resulting from rough usage in handling, as in the freight yards and warehouses, all as will be herein-after more fully described and claimed.

Referring to the accompanying drawing, which is made a part hereof and on which similar reference characters indicate similar parts,

Figure 1 is a perspective view of a hogshead head of my improved construction having a portion of the head broken away to illustrate more clearly the construction and arrangement of the parts.

Figure 2, a similar view showing the under side or bottom of the hogshead with a portion of the bottom broken away to show the interior along the line of one of the joints,

Figure 3, a cross-section on the dotted line 3-3 in Figure 1,

Figure 4, a view in elevation showing one portion of a side of the hogshead as it appears after it has been broken and repaired,

Figure 5, a sectional view on the dotted line 5-5 of Figure 4, and

Figure 6, an inside view of one of the sections of the hogshead.

The hogshead is made of panels of plywood, these panels being shown as of three-ply structure and each panel being of a length equal to the height of the hogshead to be constructed and of a width slightly more than one-half of the circumference of said hogshead, to provide for lap-joints at their edges.

In the drawing the numeral 10 indicates one of the panels, which are preferably duplicates, from which the hogshead is constructed. Along its lower edge are secured by nails or any other appropriate means a series of short cleats 11 upon which the bottom 16 of the hogshead rests when the parts are assembled. Along one edge are similarly secured a series of clips 12 having overhanging lips under which the edge of the other panel will fit and be retained. Another series of clips 13 are secured near the upper edge of each panel upon which the head of the hogshead rests when in place.

In assembling the hogshead the panels (preferably two in number) are bent into the form of semi-circles and the edge of one is slipped within the edge of the other on which the clips 12 are secured and said edge inserted beneath the projecting lips on said clips. Preferably the edge of the panel which is inserted in said clips on one side of the hogshead bears the clips on its inner face within which the edge of the other panel is inserted as most clearly indicated in Figures 1 and 2. Hoops 14 preferably of wire, are placed around the assembled parts and the ends of the wire twisted together (as at 15) to tighten the joints and to form a compact and well supported structure. The bottom 16 of the hogshead is put in place resting upon the cleats 11 as the panels are bent to form around it and thus serves to define the size of the bottom of the hogshead. The wire hoops 14 are forced into place to firmly clamp the panels not only to the bottom but to clamp their edges together within the clips 12. After the hogshead has been filled with tobacco the head 17

is put in place in the upper end thereof with its edges resting upon the cleats 13 just beneath the upper edge of each panel. A hoop or liner 20 is then secured in place inside the top edge of the hogshead by brads or any appropriate securing devices for holding the head in place. Short cleats such as cleats 11 may be used instead of the continuous lines if preferred.

- 10 In the use of a hogshead of this construction it is only necessary in order to inspect the contents to cut the wire hoops 14 by means of a pair of wire clippers when the sections will open up and permit a complete and thorough inspection of the contents from top to bottom. After inspection the joint opened up can be closed and the wire hoops again twisted to bind the parts tightly together and restore the package to perfect and complete 15 form and condition. This can be done in a very few minutes and with comparatively little trouble or labor. After the hogshead has been emptied of its contents the panels and heads may be nested and readily packed for 20 return to the shipper and the hogshead thus 25 be used repeatedly and the cost of a new hogshead for each shipment saved.

In the rough handling to which such packages are subjected occasionally one of the sides 30 becomes punctured through contact with some obstruction and the contents exposed to the weather. With my package it is an easy matter to trim out such a hole to regular proportions as indicated in Figure 4, slide a piece of 35 ply-wood 18 through the hole between the inner face of the panel and the contents until the lower end of the repair piece 18 will slip inside the hole when with a sharp tool the whole repair piece can be slid down and then 40 secured in place by wire clips, as 19, most clearly shown in Figure 5. In this way the punctured panel is restored and made substantially as good as new.

While I have described this hogshead as a 45 tobacco hogshead for which it is primarily designed, it will be understood, of course, that it may be used in the shipment of any product for which it may be found especially adapted.

It will be obvious to those skilled in the art 50 that various changes may be made in my device without departing from the spirit of the invention and I therefore do not limit myself to what is shown in the drawing and described in the specification but only as indicated by 55 the appended claims.

Having thus fully described my said invention, what I claim as new and desire to secure by Letters Patent, is:

1. A knock-down hogshead comprising a 60 pair of normally thin, flexible panels and solid disk heads, said panels being bent to encircle said heads with their adjacent edges overlapping, clips secured along one inner edge of each panel adapted to receive the edge 65 of the other panel, and bands for retaining

said panels and heads in position, substantially as set forth.

2. A knock-down hogshead composed of a pair of normally thin, flexible panels and solid disk heads, permanent cleats secured 70 along the lower inner edge of the panels to support the lower head, cleats spaced slightly below the upper edge of the panels to support the upper head, clips permanently secured along one inner edge of each panel, said 75 panels adapted to be flexed into semi-cylindrical form with their edges overlapping, said clips on one panel adapted to receive the plain edge of the other panel when assembled, the whole encircled by bands to retain said 80 panels and heads in position, and a retaining band nailed to the inner side of said panels adjacent said upper head to prevent its displacement, substantially as set forth.

In witness whereof, I have hereunto set my 85 hand at Elizabeth City, North Carolina this 2nd day of September, A. D. nineteen hundred and thirty-one.

WILLIAM BLADES FOREMAN.
